UNITED STATES PATENT OFFICE.

JOSEPH W. JONES, OF NEW YORK, N. Y.

DESIGN FOR A SPEEDOMETER-CASING.

No. 39,319.

Specification for Design.

Patented May 26, 1908.

Application filed June 10, 1907. Serial No. 378,317. Term of patent 14 years.

To all whom it may concern:

Be it known that I, JOSEPH W. JONES, a citizen of the United States, residing in the city, county, and State of New York, whose post-office address is No. 2228 Broadway, New York city, New York, have invented a new, original, and ornamental Design for a Case for Speedometers, of which the following is the specification, reference being had to the accompanying drawings, forming part hereof.

Figure 1 is a top or plan view; Fig. 2 is a side elevation, viewed from the left hand; and Fig. 3 is a bottom view.

I claim:

The ornamental design for a speedometer casing, as herein shown.

JOSEPH W. JONES.
